UNITED STATES PATENT OFFICE

WALTER R. PAXSON, OF GLENSIDE, PENNSYLVANIA, ASSIGNOR, BY MESNE ASSIGNMENTS, TO A. H. FOX GUN COMPANY, OF PHILADELPHIA, PENNSYLVANIA, A CORPORATION OF PENNSYLVANIA

CARTRIDGE FOR TOY GUNS

Application filed October 4, 1926, Serial No. 139,255. Renewed April 9, 1929.

My invention relates to cartridges for toy guns and more particularly to cartridges of a type in which no explosive is employed to project the projectile or ball but the projectile 5 is projected by the impact of a spring impelled plunger contained within the cartridge shell or casing. The cartridge forming the subject-matter of the present application and a gun in which it is adapted to be used are disclosed in a copending application of mine, filed September 26, 1925, Serial Number 58,880.

One of the objects of my invention is to make a cartridge which somewhat closely resembles in outward appearance a cartridge used in a real firearm, said cartridge being adapted to be inserted into the breech of a toy shot gun and withdrawn therefrom in the same manner as cartridges are manipulated in loading and unloading a real shot gun.

A further object of my invention is to provide a cartridge for a toy gun in which the impelling force for the projectile within the cartridge is the impact of a plunger contained with the cartridge shell, with the rear or inner side of the projectile, said plunger being impelled by the force of a spring under tension.

30 A further object of my invention is to prevent the formation within the cartridge shell or casing of air pressure between the plunger and the projectile so that the projectile or bullet is projected by impact and not by the force of air compressed behind the projectile.

40 A further object of my invention is to provide a cartridge comprising relatively few parts of simple construction, which is certain in action, durable and not liable to become inoperative, said parts and complete shell being of such construction as to be readily manufactured at a reasonable cost.

Other objects of my invention will appear in the specification and claims below.

45 Referring now to the drawings forming a part of this specification and in which the same reference characters are employed throughout the various views to designate the same parts,

Fig. 1 is a longitudinal sectional view of my improved toy cartridge;

Fig. 2 is a transverse sectional view on the line 2—2 of Fig. 1;

Fig. 3 is an end view of the cartridge shown 55 in Fig. 1;

Fig. 4 is a longitudinal axial sectional view of a somewhat modified construction; and

Fig. 5 is a transverse sectional view of the plunger and washer on line 5—5 of Fig. 4, 60 with the outer shell omitted.

The cartridge forming the subject-matter of this invention consists essentially of a metallic tube, cylinder or casing 1, which is of substantially uniform diameter inside and 65 outside except that at the discharge end thereof the shell may be provided with a tip 2, provided by forming, in any suitable manner, an annular groove 3 in and through the walls of the cylinder to provide a shoulder 4 on the inner side thereof and to limit the outward movement of the plunger, referred to below, the diameter of said tip being of substantially the same diameter as the diameter of the ball or projectile 5 but slightly 70 tapering outwardly so that the ball 5 pressed therein may be quite firmly retained therein by friction and possibly by the resiliency of the walls of the shell. The rear end of the tube or casing is provided with an 75 integral head 6, providing an annular flange 7. The center of the head 6 is offset somewhat inwardly and is provided with a relatively small opening 8 coaxial with the axis of the tube or casing 1, said offset providing a seat 80 or shoulder 9 on the outside thereof for engagement with a detent, to be referred to again below. The cartridge head 6 may be formed of the same material as the shell, in 85 any suitable manner, as by a spinning or expanding or metal drawing process.

Within the tube or shell 1 is a plunger or piston 10 of a diameter to smoothly fit and slide within the bore of the cylinder or casing 1. This piston 10 is preferably hollow, its 90 rear end being preferably open and its forward end preferably substantially closed by the transverse wall 11 which is provided with a plurality of openings 12 therethrough.

Also within the casing or shell 1 is a coiled 100

spring 13 forming the propulsion spring of the shell. The forward end of this spring 13 is preferably seated within the piston or plunger 10 against the rear side of the front wall 11 thereof, and its rear end is preferably positioned and held in place by the inwardly extending projection 14 formed by the offset on the central portion of the head 6. This spring 13 is under tension at all times, said tension being such as to normally hold it firmly against the shoulder 4 formed by the annular groove 3 in the wall of the cylinder or casing 1.

Also rigidly secured to the center of the forward wall 11 of the piston or plunger 10 is a catch or latch 15 comprising a rearwardly extending somewhat resilient arm 16, with a tapered head 17 at the free end thereof forming a notch or detent 18. From said notch or detent 18 to the end of the tapered head 17, the edge of said head is provided with a curved or rounded or tapered surface 19 and the extreme tip 17' of said head 17 is preferably considerably above the center of the cylinder or casing 1 so as to be at all times in a position to pass through the hole or opening 8 in the head and so that the curved surface 19 will be in the path of the firing pins of the gunlock mechanism when the plunger is held in its retarded position by said latch. The forward end of said catch or latch 15 is preferably riveted to the plunger or piston 10 to form a projecting rounded head 20, slightly in advance of the forward face of the wall 11 of the piston or plunger 10. When the piston or plunger 10 is at the forward limit of its motion against the annular shoulder 11, the forward end of the head or projection 20 will be within the space occupied by the ball or projectile 5 when it is seated within the tip 2 and therein frictionally retained, as is clearly shown in Fig. 1.

It is to be understood that the annular groove 3 is not placed or formed in the cylinder or casing 1 until after the spring 13 and the plunger 15 with the latch extending rearwardly therefrom have been placed within the cylinder 1, whereupon the piston 10 is permanently retained within the cylinder by spinning, or pressing inwardly the groove 3 to form the shoulder 4.

With the parts thus assembled, in order to "load" the shell it is only necessary for one to force a stick or ramrod into the shell, pressing against the forward end of the piston or plunger 10, and forcing it rearwardly until the tapered head 17 on the rear end of the resilient arm 16 shall enter and pass through the opening 8 in the piston head. As this tapered end 17 enters the opening 8 in the head, the curved surface 19 between the point 17' and the detent or tooth 18 engages the wall of the hole 8 and, as the rearward motion of the plunger continues, this surface 19 rides over said edge springing the resilient

arm 15 slightly to permit the notch or detent 18 to ride over the edge of the opening 8 and spring back to bring the square shoulder 21 of the notch against the seat or shoulder 9 surrounding the opening 8. When the piston has been thus forced back to the position last described, pressure on the ramrod used in forcing the plunger or piston 10 may be released and the tooth or detent 18 engaging the seat 9 will retain the plunger 10 in its retracted position with the propulsion spring 13 under relatively great tension. When the plunger is thus held in its retracted position, the projectile 5 is forced into the tip 2 and is frictionally held there as above described. This projectile is preferably a ball or sphere of light soft wood and since it has no sharp projection on the surface thereof and has little weight or mass, it may be projected at a rather high speed without incurring danger of seriously injuring one who might be hit by the projectile in its flight.

When the shell has thus been loaded it is adapted to be inserted into the breech of a gun, such as is shown in my copending application and when so mounted the tapering surface 19 of the head 17 of the resilient arm 16 will be in a line with the firing pin of the gun so that when the firing pin is forced forwardly by pulling the trigger, it will engage said curved surface 19 and force it toward the axis of the shell or casing 1 sufficiently to move the notch or detent 18 out of engagement with the seat or shoulder 9 surrounding the opening 8, whereupon the tension of the propulsion spring 13 will impel the plunger or piston 10 forwardly at a high rate of speed until it shall come to rest on or be stopped by the annular shoulder 4 inside of the shell or casing 1, but before coming to that position the projection or head 20 on the forward side of the wall 11 will engage and strike a sharp blow against the ball or projectile 5 and impel it through the barrel of the gun.

Thus it is that the ball is projected by the force of the impact of the spring impelled plunger against the projectile. Because of the holes or openings 12 through the forward wall 11 of the hollow plunger or piston 10 the pressure on both sides of the piston will be substantially equalized, that is to say, no substantial pressure will be built up within the shell between the forward end of the piston or plunger 10 and the projectile before it is struck by the plunger or piston 10 so that the ball is projected by the force of the impact and not by the force of air compressed between the plunger or piston and ball or projectile.

The central portion of the cartridge head 6 is offset inwardly so that when the shell is "loaded" the tapered head 17 of the arm 16 will not substantially project rearwardly beyond the plane of the rear surface of the flange 7 of the head 6 and so that the said

head 17 will not engage the forward end of the frame of the gun when the breech is closed and will clear the firing pins when they are in their most rearward position out of contact 5 or engagement with the tapered heads 17 projecting rearwardly through the cartridge head 6. When, however, the firing pins are moved forwardly by pressure on the triggers of the gun, the forward ends of the firing pins 10 will engage the curved surface 19 of the head 17 and slide the tooth or notch 17 off its seat or shoulder 16 on the head to release the plunger or piston 10.

In the modified construction illustrated in 15 Figs. 4 and 5, the arm 16' of the latch 15' is not resilient as in the construction above described but is pivotally mounted within the plunger 10' on a transverse pivot pin 22, the ends of which are mounted in diametrically 20 oppositely alined holes 23 extending through the cylindrical wall of said plunger, said pin 22 also fitting within bushings 24 on opposite sides of the latch 15'. These bushings extend respectively, from a side of the latch to the 25 wall of said plunger and maintain the said latch 15' in a position substantially central to the plunger and shell. The latch 15' is also preferably provided with a rearwardly extending arm 25, the free extremity of which is 30 curved outwardly to extend substantially radially to the axis of the shell and to bear against the inner side of the wall 11' of the plunger 10' when the tooth or detent 18 is in engagement with the shoulder or seat 9 out- 35 side of the edge of the hole or opening 8. In other words, when the free end of the arm 25 is in engagement with the wall 11' the detent will be in a position to hold the plunger in its retracted position after the notch or detent 40 18 has passed through the opening 8 and the surface 21 thereof is seated on the annular seat 9. As the tooth or detent 18 rides over the wall of the hole 8, the free end of the arm 25 will move outwardly and forwardly slightly 45 away from the wall 11'. Surrounding the free end of the arm 25 and slidingly fitting within the bore of the plunger 10' is a cup or washer 26, preferably having a diametrically extending slot 27 through which the 50 arm 25 passes. The forward surface of the cup or washer bears against the rear side of the free end of the arm 25 and within the cup is seated one end of the coiled propulsion spring 13' which is at all times under 55 compression, and, therefore, normally yieldingly holds the rim of the washer 26 against the rear edge of the free end of the arm 25 and the forward free edge of said arm against the head 11' of the plunger.

60 To prevent the cup or washer 26 from binding or cramping within the bore of the plunger 10', the washer is preferably provided with a segmental flange 28 projecting forwardly from the washer a distance substantially equal 65 to the thickness of the free end of the arm 26.

So constructed, the compressive force of the spring does not tend to twist the washer within the bore around the point of the engagement of the edge of the slot 27 with the rear edge of the arm 25.

When assembled, the transverse pin 22 and bushings 24 will extend between the convolutions of the spring 13'.

In order that the plunger 10' may project forwardly a distance sufficient to impinge 70 against the ball or projectile 5 seated in the tip 2, I may provide the forward wall 11' of the plunger with a dome-like projection 20' which, like the rivet head 20 of the latch 16, will strike the projectile 5 a sharp blow when 75 the plunger is projected against the shoulder 4 by the release of the latch 15' from its engagement with the seat 9 surrounding the hole 8 in the rear end of the shell. The head 17, the tip 17', the curved surface 19 and the 80 squared surface 21 of the tooth or notch 18 are like and operate precisely as they do in the embodiment of my invention first above described. In the construction shown in Figs. 85 4 and 5, the propulsion spring 13', in addition to supplying the force to project the plunger 90 forwardly, also constitutes the means for yieldingly holding the latch 15' in a position to take over the forward edge of the hole 18 when the plunger is forced to its rearmost 95 position and to maintain the curved surface 19 to lie across the axis of the firing pins so that when the firing pins are forced forwardly they will surely contact with the curved 100 cam surface 19 of the head 17, force the latch 15' toward the axis of the shell and release the latch from its engagement with the shoulder or seat 9.

Having thus described my invention, what I claim and desire to protect by Letters Patent 105 of the United States is:

1. A shell for toy guns comprising a shell, a plunger therein, a spring for driving said plunger, means for holding said plunger remote from the discharge end of said shell and 110 said spring under tension, and a projectile removably mounted in the discharge end of the shell, spaced from said plunger and in a position to be projected by the impact of said plunger against said projectile.

2. A shell for toy guns comprising a shell, a plunger therein, a spring for operating 115 said plunger, means for holding said plunger retracted in said shell with said spring under tension, and a projectile removably mounted in one end of the shell and spaced from said piston when retracted, said plunger being provided with openings to permit the passage 120 of air therethrough.

3. A shell for toy shotguns comprising a cylindrical shell, having one end shaped to hold a projectile, the end of the shell remote from said projectile holding end being provided with a relatively small opening, a plunger 125

in said shell and having a clear passage for air therethrough, a releasing finger carried by said plunger and having a tapered head for engagement with the edge of the opening to hold the plunger in its inward position within the shell and remote from said projectile, and a spring for driving said plunger forwardly to impinge against said projectile when said finger is moved to release said plunger.

4. A shell for toy shot guns comprising a cylindrical shell, having one end shaped to hold a projectile, the end of the shell remote from said projectile holding end being provided with a relatively small opening, a plunger in said shell, a releasing finger carried by said plunger and having a tapered head for engagement with the edge of the opening to hold the plunger in its inward position within the shell and spaced from said projectile, and a spring for driving said plunger forwardly to impinge against said projectile, said head on said releasing finger being tapered and having its terminal point positioned at one side of the central axis of the shell.

5. A shell for toy shotguns comprising a cylindrical shell, having one end shaped to frictionally hold a projectile, the end of the shell remote from said projectile holding end being provided with a relatively small opening, a plunger in said shell, a releasing finger carried by said plunger and having a tapered head for engagement with the edge of the opening to hold the plunger in its inward position within the shell and spaced from said projectile, and a spring for driving said plunger forwardly to impinge against said projectile, said plunger being provided with openings to permit the passage of air therethrough, and to prevent any substantial compression of air between said plunger and said projectile during the forward movement of said plunger.

6. In a cartridge for a toy gun, the combination of a substantially cylindrical shell having a tip of slightly reduced diameter providing a shoulder near the discharge end of said shell, a slightly outwardly tapering bore between said shoulder and the discharge end of said shell for frictionally retaining a projectile therein, a plunger slidably fitting in said shell and having a projection on the forward end thereof, a compression spring in said shell operative to normally hold said plunger against said shoulder and with said projection extending into said tapering bore, and a latch mounted in said shell for retaining said plunger in a retracted position away from said shoulder and spaced from said projectile, in opposition to the tension of said spring.

7. In a cartridge for toy guns, the combination with a substantially cylindrical shell

having a shoulder near the forward end thereof and the head with a central opening therethrough at the rear end thereof, a plunger slidable in said shell and retained therein by said shoulder, a propulsion spring under tension, normally yieldingly holding said plunger against said shoulder, and a latch carried by said plunger and extending rearwardly within said shell and having a detent near the free end thereof and a transversely flat, longitudinally curved surface extending from said detent to the free end of said latch lying diametrically across the axis of said shell and normally across the edge of the opening through said head, the said latch being yieldable in a plane passing through the axis of said shell in a direction inwardly away from the edge of said opening, whereby when said plunger is pressed rearwardly against the tension of said propulsion spring said curved surface slides over the edge of said opening to bring said detent into engagement with the outer surface of said head adjacent said opening to hold said plunger in a retracted position against the tension of said propulsion spring, said curved surface also forming the firing-pin-engaging surface to release said detent from the edge of said opening.

8. In a cartridge for a toy gun, the combination of a substantially cylindrical shell with a discharge tip of tapering bore flaring outwardly from within the shell to frictionally retain a spherical projectile therein and to provide an inwardly directed shoulder at the rear end of said tapering bore, a cartridge head substantially closing the rear end of said shell, a plunger mounted in said shell to reciprocate longitudinally thereof and having a projection at the front end and centrally thereof, a compression spring normally yieldingly holding said plunger against said shoulder with said projections extending beyond said shoulder, and a latch mounted in said shell to releasably retain said plunger in a retracted position relatively remote from said shoulder, said shoulder being operative to permanently retain said plunger within said shell, said spring being operative to impel said plunger forwardly to cause said projection to impinge against said projectile before said plunger engages said shoulder.

9. In a cartridge for toy guns, the combination of a shoulder near the forward end thereof, a plunger reciprocable in said shell, a cartridge head substantially closing the rear end of said shell, a compression spring normally holding said plunger against said shoulder and a latch mounted in said shell for retaining said plunger when forced inwardly against the tension of said spring, in a retracted position relatively remote from

said shoulder, said shoulder being so positioned with respect to a projectile frictionally retained therein that said plunger when released from its said retracted position impinges upon said projectile immediately before it engages said shoulder.

10. In a cartridge for toy guns, the combination of a shoulder near the forward end thereof, a plunger reciprocable in said shell and having a free passage for air therethrough, a cartridge head substantially closing the rear end of said shell, a compression spring normally holding said plunger against said shoulder and a releasable latch 15 for retaining said plunger when forced inwardly against the tension of said spring, in a retracted position relatively remote from said shoulder, said shoulder being so positioned with respect to a projectile frictionally retained therein that said plunger when released from its said retracted position impinges upon said projectile before it engages said shoulder.

15. In witness whereof, I have hereunto set
20 my hand this first day of October, 1926.

WALTER R. PAXSON.
